UNITED STATES PATENT OFFICE.

JAMES F. CONOVER, OF CHICAGO, ILLINOIS.

PIANO TUNING-PIN.

No. 921,203.

Specification of Letters Patent.

Patented May 11, 1909.

Application filed August 22, 1907. Serial No. 389,727.

To all whom it may concern:

Be it known that I, JAMES F. CONOVER, a citizen of the United States of America, and resident of Chicago, Illinois, have invented a 5 certain new and useful Improvement in Piano Tuning-Pins, of which the following is a specification.

My invention relates to improvements in stringing pianos, having particular reference 10 to improvements in pins and means for securing them in position.

The object of my device is the production of means by which the tension of the piano 15 strings may be varied without loosening the pins.

A further object is the production of a device by means of which the resiliency of the wood of the wrest-plank serves better to prevent the pin from turning back under the 20 pull of the strings.

A further object is the production of a device that can be readily fitted in place in a piano, and will increase the efficiency of the instrument.

25 A further object is the production of a device by means of which the pins are prevented from enlarging the holes and destroying the resiliency of the fibers of the wood of the wrest-plank.

30 A further object is the production of a device by means of which the contact of the sleeves and pins is such as to cause the pins to move easily and smoothly in the process of tuning the instrument.

35 A further object is the production of a device of simple construction and one that can be cheaply manufactured.

These and such other objects as may hereinafter appear are attained by my device, 40 embodiments of which are shown in the accompanying drawings, in which—

Figure 1 is a sectional view of a portion of a piano frame showing my improved device in position. Fig. 2 is a transverse sectional 45 view taken through the pin in position.

Like numerals of reference indicate like parts in the several figures of the drawings.

Referring to the drawing by reference 50 numerals, 8 designates the wrest-plank and 9 the string. The strings are secured at their upper ends by being wound around the top portion of a pin 11 provided with a squared head 12. The wrest-plank is provided with a series of holes 13 in which fit sleeves or 55 sockets 14, and within which sleeves the tuning pins 11 are seated. These sleeves 14

are formed from a single strip of metal having corrugations 15—15 on their outer surface. The sleeve is preferably split, as shown at 16. A flange 17 is turned outwardly on the top of the sleeve, which prevents the sleeve from falling through the wrest-plank. The inside of the pin sleeve 60 forms a smooth surface.

The method of stringing the piano is as 65 follows: Holes are bored in the wrest-plank in proper position, and of a diameter fitting the outer diameter of the pin sleeve 14. These pin sleeves are then placed in the holes 13, the corrugations 15—15 resting against the 70 fiber of the wood surrounding the holes. The pin 11 is of a greater external diameter than the internal diameter of the sleeve 14, and is provided with a rounded end 19. This end is inserted in the mouth of the pin 75 sleeve, and the pin driven within the sleeve. By this operation, the sleeve is expanded. This operation forces the corrugations of the sleeve against the fiber of the wood and forces the fibers of the wood of the wrest- 80 plank into a resilient state, which in turn produces a counter force upon the sleeve clamping it upon the pin producing the friction which holds the pin from turning back under the strain of the string 9. The string 9 85 is rigidly secured at its lower end to the usual hitch pin and wound about the upper end in coils 20, as shown in Fig. 1. It will be noted that the last coil of the string is close to the flange 17; consequently the strain of the 90 string is brought against the pin just above the top of the wrest-plank. By this means the danger of springing the pin (which would happen if the force were brought higher up on the pin) is avoided. The end of the pin is 95 squared, as shown at 12, so that by means of a wrench the tension of the strings may be varied at will.

Heretofore in stringing pianos, it has been customary to simply drive the tuning pin 100 11—which was preferably formed with minute threads—into holes bored in the wooden wrest-plank, trusting to the pressure of the wood against the pin to hold the pin securely in place. It is evident that in tuning the 105 piano, it is necessary to often turn the pin in both directions,—that is, the tension of the string is often made greater than desired, necessitating the turning back of the pin. This necessarily loosens the pin within its wooden 110 socket. Inasmuch as there is in some cases a tremendous tension on these strings, run-

ning from one hundred and twenty five to five hundred pounds per string, and aggregating as high as seventy thousand pounds on the piano frame, it is evident that there is great danger in loosening the hold of the wood on the pin, and any loosening, however slight, affects the tone of the note produced by the string. In varying the tension by turning the pins, there is a gradual wearing away of the wood of the plank adjacent thereto, which enlarges the holes and destroys the resiliency of the wood. When this enlargement of the holes amounts to say two or three one thousandths of an inch, the pins will no longer stand, and larger ones must be substituted. To provide for this, tuning pins are generally made for several sizes the diameters increasing by five one thousandths of an inch. In view of the gradual enlargement of the holes, the pins are driven as tightly into the plank as can be without causing the pin to twist off when turned in tuning. Hence, in tuning the piano, the force exerted to start the pin is so great that it usually causes the pin to move beyond the desired point, and it must, therefore, be turned back in order to give the proper tension. This abrupt movement of the pin makes it difficult to correctly tune the instrument. With my invention, these defects are practically overcome. The tension of the strings can be varied without loosening the pins, for the reason that the force which holds them in place is constant as the resiliency of the fiber of the wrest-plank is not destroyed by crushing while turning the pin under the strain of the string.

The pins turn easily and smoothly from

the nature of the friction between the two metal surfaces, and because the binding force need be no greater than just enough to hold the pin from turning back under the strain of the string. 40

I claim:

1. In a piano, the combination with a wrest-plank, a split cylindrical sleeve having a smooth inner surface, an irregular outer surface substantially parallel with the inner surface, an outwardly turned flange formed on the upper end thereof, a cylindrical pin having a smooth outer surface, and a diameter greater than the internal diameter of said sleeve. 45 50

2. As a new article of manufacture, a split cylindrical sleeve having a smooth inner surface, an irregular outer surface substantially parallel with the inner surface, an outwardly turned flange formed on the upper end thereof, a cylindrical pin having a smooth outer surface, and a diameter greater than the internal diameter of said sleeve. 55 60

3. As a new article of manufacture, a split cylindrical sleeve having a smooth inner surface, a vertically corrugated outer surface substantially parallel with the inner surface, an outwardly turned flange formed on the upper end thereof, a cylindrical pin having a smooth outer surface, and a diameter greater than the internal diameter of said sleeve. 65 70

Signed by me at Chicago, Illinois, this 31st day of July, 1907.

JAMES F. CONOVER.
